UNITED STATES PATENT OFFICE.

IRVIN J. HANDLEN, OF GREEN BAY, WISCONSIN.

CONFECTIONERY MACHINE.

Application filed May 19, 1926. Serial No. 110,163.

The present invention relates generally to the confectionery art and has more particular reference to a machine that is primarily adapted for use in the formation of candy bars of circular shape in cross section, the primary object of the invention residing in the provision of certain improvements upon Letters Patent No. 1,570,247 issued to me on the 19th day of January 1926.

10 A very important object of the invention lies in the provision of means whereby the machine may be adjusted in a quick and efficient manner for rolling different sizes of candy bars without the necessity of changing any parts thereof.

15 A still further very important object of the invention is to generally improve upon a machine of this nature by providing an exceeding simple structure which is strong, durable, easy to manipulate, reliable in operation, not likely to easily become out of order, capable of assembly and disassembly for cleaning, repair, and renewal purposes, and otherwise well adapted to the purpose 20 for which it is designed.

With the above and numerous other objects in view as will appear as the description proceeds, the invention resides in certain novel features of construction, and in 25 the combination and arrangement of parts as will be hereinafter more fully described and claimed.

In the drawing:

Figure 1 is a side elevation of the machine 30 embodying the features of my invention,

Fig. 2 is a top plan view thereof,

Fig. 3 is an end elevation thereof, looking at the delivery end,

Fig. 4 is a detail view of one side of the 40 frame of the machine,

Fig. 5 is a detail elevation of the delivery end of the machine showing the belt wheel removed,

Fig. 6 is a plan view of the material 45 guide member that forms an essential part of this invention,

Fig. 7 is a plan view of one end member,

Fig. 8 is a plan view of the other end member,

50 Fig. 9 is a fragmentary plan view of the guide member, and

Fig. 10 is a side elevation of the material guide.

Referring to the drawing in detail, it will 55 be seen that a confectionery machine constructed in accordance with the present in-

vention includes a base 5 of relatively long, and narrow configuration upon one end of which is supported a suitable form of prime mover such as an electric motor 6.

The machine per se, embodies the provision of a pair of side frame members 7 that are also relatively long and narrow and are formed with relatively large cut out portions 8 for the purpose of lightness and cheapness. Each of these side frame members is formed adjacent its opposite ends with depending legs 9 and 10 of varying lengths. These legs are adapted to be rigidly secured to the opposite side edges of the base 5, it being of course noted that due to the variation in the length of the legs, the side frame members 7—7, will be supported at an inclination with respect to the longitudinal plane of the base 5.

Between these side frame members 7 is an upper and a lower endless belt 11 and 12 respectively, that are clearly shown in Fig. 1. These belts are disposed in spaced relationship with each other. The inclined ends of these belts are trained over flanged rollers 13 and 14 respectively that are in turn carried by shafts 15 and 16, the ends of which are disposed in suitable bearings.

These bearings 15' and 16' are adjustable thru bolts 14', or in any other preferred manner. The lower rear ends of these endless belts 11 and 12 are in turn trained over flanged rollers that are carried by shafts 17 and 18 respectively, journaled in suitable bearings in said side members 7. Certain ends of these shafts 17 and 18 extends beyond the adjacent side frame member 7 and the end of the uppermost shaft 17 is equipped with a spur gear 19 that is in mesh with a spur gear 20 carried by a stub shaft 21 and this gear 20 is in turn in mesh with a relatively large spur gear 22 upon the end of the lowermost roller carrying shaft 18. As is more clearly shown in Fig. 5, the stub 95 shaft 21 is carried by a lever 40 having a pin and slot connection 41 with the adjacent side frame member 7, for a purpose which will be apparent later, as the description proceeds.

The shaft 18 carries a relatively large pulley wheel 23 over which is trained an endless belt 24 that extends forwardly and is trained over another smaller pulley 24 upon the end of the armature shaft of the 110 motor 6, it being of course apparent that the relationship between the two gears 22

and 19 is such that the uppermost endless belt will move relatively faster than will said lowermost belt 12 for purpose presently to be set forth.

5 Disposed intermediate the ends of said side frame member 7 is a pair of flanged guide rollers 25 over which said belts 11 and 12 pass, these rollers obviously act as guides for the belts and prevent the same from sagging in the center during the operation of the machine.

It is preferable that the belts 11 and 12 at their lower discharge ends be more closely related than is the case with said belts at 15 their inlet ends for obviously compensating for the gradual decreasing of the cross sectional area of the candy moving in a downward direction, which movement is obviously occasioned by the reverse movement of 20 adjacent faces of the said belts as well as the faster speed of the uppermost belt 11.

Extending longitudinally between said belts 11 and 12, is a material guide designated generally by the reference numeral 25 26. This material guide comprises a pair of spaced parallel legs 27, the opposite ends of which are flared outwardly as is clearly shown in Fig. 6. Certain ends of the legs of this guide member are joined together 30 by a cross web 28, while the opposite outwardly flaring ends of said legs are formed with dove-tailed shape lugs 29. This material guide is positioned in a manner as is clearly shown in the side elevational view, 35 Fig. 1, it being noted that the connecting web 28 between the legs 27 of this guide, serves as receiving trough for the balls of candy to be formed in the rolls by the action of the cooperating endless belts 11 and 12.

40 At the discharge end of the machine, there is positioned a receiving table 30 that extends slightly inwardly between the side member 7—7. From the description as it has thus far progressed, it will be seen that 45 the structure is practically identical in principal with that disclosed in my said patent. Particular attention is now directed to the improvements.

The side frames 7 are each formed from 50 a pair of sections, the upper section being denoted by the numeral 42 and each lower section by the numeral 43. These sections have at their ends outwardly projecting ears 44 pierced by bolts 45 having springs 46 55 thereon urging said ears apart. As is clearly indicated in Fig. 5, these bolts are reduced where they pierce the ears and are threaded- 60 ly engaged as at 47 with the lower ears 44. By this adjustment, it will be seen that the distance between the belts may be varied 65 thereby regulating the size of the roll of candy. Obviously when the sections 42 are moved away from or toward the section 43 of the side frame member 7, the gears 19 and 22 are spaced different distances apart, and

thus the lever 40 may be swung so that the idler gear 20 properly meshes therewith.

A U-shaped connecting member 49 is at the front end of the machine and is fixed as at 50 to the lower sections 43 and has a pin and slot connection as at 51 with upper sections 42. A U-shaped connecting member 53 is fixed at 54 to the lower sections and has a pin and slot connection 55 with the upper section. The sides of the connecting members 53 are provided with dove-tailed mortises for receiving the dove tailed tongues 29 of the material guide member 27. The intermediate portion of this guide member including the web 28 rests on the intermediate portion of the connecting member 49 as is clearly illustrated in Fig. 2.

Another improvement lies in the provision of a manually actuated follower clearly shown to the right of Figs. 2 and 6 and in Fig. 9. This follower includes a plate 60 having an elongated longitudinal slot 61 for receiving a stud 62 comprising from the web 28. A handle 63 is provided on the plate and an abutting member 64 is provided at the end of the plate. A spring 65 engages the member 64 and the stud 62 normally holds the plate as is shown in Figs. 2 and 6. The plate is pushed inwardly as is shown in Fig. 9, thereby tensioning the spring to automatically return the same when released. When the follower is thus pushed in, the balls are fed in between the belts as will be apparent.

A pair of spaced parallel guide ribs 66 are provided on the web 28 between which the plate 60 moves. A trough 67 is provided under the belts and feeds into a suitable receptacle 68 so that none of the material will be wasted.

From the foregoing description, when considered in conjunction with the accompanying drawings, it will be at once apparent to those skilled in the confectionery art, that I have provided a highly novel and simplified form of the machine disclosed in my said patent. The present embodiment of the invention has been disclosed in detail, merely by way of example, since in actual practice it attains the features of advantages enumerated as desirable in the statement of the invention and the above description.

It will be apparent that numerous changes in the details of construction, and in the combination and arrangement of parts may be resorted to without departing from the spirit or scope of the invention as herein-after claimed or sacrificing any of its advantages.

Having thus described my invention, what I claim as new is:—

In a candy rolling machine of the character described, a pair of side frame members, each side frame member including an

upper section, and a lower section, means for spacing the sections apart and allowing for adjustment therebetween, a pair of endless belts one between the upper sections 5 and one between the lower sections, means for moving said endless belt so that their adjacent faces will move in opposite directions, said means including a pair of gears, one associated with each belt, an idler gear 10 therebetween and in mesh therewith, a stub

shaft for said idler gear, a lever, said stub shaft being carried by said lever, and a pin and slot means for mounting said lever on one of the frame sections whereby the lever may be swung to shift the idler in proper 15 mesh with the pair of gears when the space between the gears is varied by the adjusting of the sections.

In testimony whereof I affix my signature.
IRVIN J. HANDLEN.
